UNITED STATES PATENT OFFICE.

GEORGE A. BOMANN, OF PLAINFIELD, NEW JERSEY.

DESIGN FOR AN ARTICLE OF MANUFACTURE.

52,466.

Specification for Design. Patented Sept. 24, 1918.

Application filed March 28, 1918. Serial No. 225,359. Term of patent 3½ years.

To all whom it may concern:

Be it known that I, GEORGE A. BOMANN, a citizen of the United States of America, residing at Plainfield, in the county of Union and State of New Jersey, have invented a new, original, and ornamental Design for an Article of Manufacture, of which the following is a specification, reference being had to the accompanying drawing, forming part thereof—

The figure is a plan view of portion of a printed fabric showing an embodiment of my new design. It is to be understood,

however, that my new design may be applied not only to fabrics but also to wall paper, wrapping paper, or similar articles having surface ornamentation, without departing from what I claim as my invention.

I claim:—

The ornamental design for an article of manufacture, substantially as shown and described.

GEO. A. BOMANN.
